(57) **CLAIM**

The ornamental design for a substrate with camouflage pattern, as shown and described.

DESCRIPTION

The file of this patent contains at least one drawing/photograph executed in color. Copies of this patent with color drawing(s)/photograph(s) will be provided by the Patent and Trademark Office upon request and payment of the necessary fee.

The sole FIGURE is a plan view of a substrate with camouflage pattern showing our new design in color. A repeat unit of the design is enclosed within the broken lines of the drawing. The broken lines do not form any part of the claimed design.
